G. W. LAMBERT.
WINDOW SASH FASTENER.
APPLICATION FILED SEPT. 24, 1913.

Patented June 30, 1914.

UNITED STATES PATENT OFFICE.

GEORGE WILLIS LAMBERT, OF RICHMOND, VIRGINIA.

WINDOW-SASH FASTENER.

1,101,859.

Specification of Letters Patent. Patented June 30, 1914.

Application filed September 24, 1913. Serial No. 791,546.

To all whom it may concern:

Be it known that I, GEORGE W. LAMBERT, a citizen of the United States, and a resident of Richmond, county of Henrico, State 5 of Virginia, have invented certain new and useful Improvements in Window-Sash Fasteners of which the following is a full and clear specification, reference being had to the accompanying drawings, in which—

10 Figure 1 is a face view of a window frame provided with my invention; Fig. 2 a vertical sectional view thereof; Fig. 3 an enlarged detail view of the frictional slide; Fig. 4 a horizontal section on the line 4—4 15 of Fig. 2; and Fig. 5 a view like Fig. 3, but showing a modification.

The object of this invention is to provide simple means for holding the sash in a tilted open position, whereby the desired ventilation may be had without admitting dangerous and troublesome currents of air into the room and whereby also the sash may be adjusted to a convenient position for cleaning operations, as more fully hereinafter 25 set forth.

This invention has relation especially though not exclusively to that class of windows in which the sash *a* is pivoted at its lower end, as indicated by the letter *c*, to the 30 lower ends of a pair of sash-supporting vertical bars or shoes *b* which are adapted to slide vertically within the usual grooves in the inner faces of the window frames, a suitable snap-fastener or other locking device *d*, *d'* 35 being employed to detachably lock the sash in vertical alignment with the bars *b*; that is, in a closed position. The weight cords are as usual attached to the strips or bars *b* so that when the sash is closed the bars *b* 40 and the sash move up and down together in the same manner as the ordinary window sash. When it is desired to ventilate the room or to bring the sash to a desirable position for cleaning, the upper end of the 45 sash is pulled forcibly inwardly to disconnect the snap-fastener *d*, *d'* and the sash is held in its adjustable position by suitable mechanism.

My invention has relation to means for 50 thus holding the sash in its open position.

In its preferred form, my invention consists of a pair of flat metallic links *e* pivoted at their lower ends at *f* to the outer edges of the sash, the adjacent edges of the sash being 55 recessed, as at *g*, for the reception of these

links *e*, so that the adjacent edges of the shoes *b* and the sash *a* may come close together when the sash is closed. The upper ends of the links *e* are each connected to the bars *b* in such manner that the sash may 60 be forcibly swung upwardly or pulled downwardly and when released will remain in its adjusted position, thereby doing away with all locking and latching devices to hold the sash in its adjusted position. The preferred 65 manner of accomplishing this consists in pivotally attaching the upper end of each link *e* to the outer face of a vertical bar *g*, which is adapted to slide vertically in a cavity formed in the supporting bar. Along 70 the opposite sides of this vertical cavity is arranged a pair of friction bars *h* whose facing edges are escalloped. The bar *g* is adapted to slide up and down between these escalloped edges, and, to cause the bar *g* to 75 have frictional engagement with the escalloped edges, said bar is provided upon its opposite side edges with springs *i*, which bulge outwardly from the bar sufficiently to resiliently engage in the recesses of the bars 80 *h*, the springs being shaped so as to fit within the curved recesses. Recesses in the bars *h* are preferably arranged opposite each other and the bar *g* is preferably provided with two springs on each side, one 85 being arranged at the upper end and the other at the lower end of the bar. With this construction, it will be observed that a forcible push upwardly on bar *g* or a downward pull thereon will cause the curved projections 90 on the bars *h* to sufficiently flatten the convexed springs to enable them to pass the apexes of the projections.

It is intended that these springs shall be sufficiently strong to prevent the weight of 95 the sash and strong wind from disturbing the adjustment of the sash, but at the same time be sufficiently resilient to enable the sash to be sprung upwardly or downwardly by the application of sufficient manual force. 100

It will be observed that this invention is susceptible of modification without departing from the spirit of the invention; in Fig. 5 I have shown a modified device in which the bars *h* are provided with V-shaped teeth 105 instead of the rounded projections shown in Fig. 3, and, instead of springs *i*, I show a pair of bow springs *i'* provided with projections *i''* adapted to fit into the projections on the bars *h*. 110

Having thus described my invention, what I claim is:—

1. In combination, a support, a swinging sash member having one end pivoted to said support, a link pivotally connecting the swinging member and the support, and means whereby the end connected to the support has a frictional longitudinal adjustment thereon, said means consisting of a serrated bar attached to the support, and a bar pivotally attached to the link, this latter bar carrying a plurality of resilient projections having frictional engagement in the serrations of the aforesaid bar.
- 5 2. In combination, a support, a swinging sash member having one end pivoted to said support, a link pivotally connecting the

swinging member and the support, and means whereby the end connected to the support has a frictional longitudinal adjustment thereon, said means consisting of a pair of oppositely facing serrated bars, a bar adapted to slide between said serrated faces and pivotally connected to said link, said sliding bar being provided with resilient 20 frictional means engaging said serrated faces.

In testimony whereof I hereunto affix my signature in the presence of two witnesses.

GEORGE WILLIS LAMBERT.

Witnesses:

J. B. MONTCASTLE,
IRWIN WEINGER.
